DESIGN.

No. 32,667.

Patented May 15, 1900.

A. A. CUSHMAN.
FURNACE BODY.

(Application filed Sept. 28, 1899.)

UNITED STATES PATENT OFFICE.

AMOS A. CUSHMAN, OF MANSFIELD, OHIO, ASSIGNOR OF ONE-HALF TO
CHARLES S. HILL, OF SAME PLACE.

DESIGN FOR A FURNACE-BODY.

SPECIFICATION forming part of Design No. 32,667, dated May 15, 1900.

Application filed September 28, 1899. Serial No. 731,984. Term of patent 7 years.

To all whom it may concern:

Be it known that I, AMOS A. CUSHMAN, a citizen of the United States, residing at Mansfield, in the county of Richland and State of Ohio, have invented and produced a new and original Design for Furnace-Bodies, of which the following is a specification, reference being had to the accompanying drawings, forming part thereof.

- 10 Figure 1 is a perspective view. Fig. 2 is an end view.

As shown in the drawings, the leading or material feature of my design consists in the series of inclined chambers arranged in the 15 form of a **W** and an enlarged chamber located at one end and a plate located at one end of the enlarged chamber.

In the accompanying drawings, 1, 2, 3, and 20 4 represent the **W** portions of the frame and are provided with rectangular sides 5, which sides are connected together at the meeting-points 6. The top or upper end of the **W** portion 1 is provided with the plain top 7, which plain top is arranged as shown. Above 25 the meeting-point of the **W** portions 2 and 3 is located the plain surface 9. The bottom or lower portions of the sections 1 and 3 are

provided with the outward lateral-extending curved flanges 10, said flanges being of the form shown in the drawings. The bottom or 30 lower portions of the sections 1 and 2 are provided with the flanges 11, which flanges are tapered or provided with the inclined sides 12. The enlarged portion or chamber 13 is provided with the curved top 14 and the 35 straight bottom 15. The plate 16 is provided with the parallel and vertical edges 17 and the rectangular openings 18 and 19, said plate being substantially of the form shown in the drawings, and as shown its top or upper end 40 is provided with the straight edge portions 20 and the curved center 21.

Having fully described my invention, what I claim as new, and desire to secure by Letters Patent, is—

The design for a furnace-body, substantially as shown and described.

In testimony that I claim the above I have hereunto subscribed my name in the presence of two witnesses.

AMOS A. CUSHMAN.

Witnesses:

C. S. HILL,
LOUIS ARTING.
